FLAMMABILITY TESTER

James R. Blegen, Pottstown, Pa., assignor to The Society of the Plastics Industry, Inc., a corporation of New York

Application May 14, 1949, Serial No. 93,217

10 Claims. (Cl. 73—432)

1

This invention relates to an apparatus for testing the flammability characteristics of combustible sheeted material such as plastic films, fabrics and the like, and more particularly comprises an apparatus for automatically testing the ease of ignition and rate of burning of such sheeted material.

This invention comprises a box-like cabinet having an ignition member such as a predetermined pointed flame located inside. A guideway set at a diagonal angle is directed toward the flame which is positioned near the bottom of the guideway. A switch is also located at the lower end of the guideway which is operated by the weight of the loaded sample holding rack, so that as soon as the rack is slid into place where the flame can strike the sample, the first timing operation is initiated.

I find it very advantageous to hold each sample in a rack which is readily removable. A number of these sample holding racks can be provided and samples can be mounted and threaded up in advance. It is an important feature of my invention that these racks are capable of holding the sample firmly in place without the necessity of using supporting wires. I have found that supporting wires tend to transmit heat from the burning sample and give false results. To accomplish this result the removable rack is U-shaped with the open end insertable first so that a free edge of the sample is accessible to the ignition flame.

The holding rack is made with an upper and lower member and the sample is clamped between these two. The upper holding member has projecting edge portions which slide on the guideway in the cabinet and the sample to be tested is held pressed against the under surface of the upper part of the holding rack. This means that the upper surface of the material to be treated is always in the plane of the upper surface of the guideway irrespective of the thickness of the material under test. As a result, the spacing from the ignition flame to the test sample is always the same.

Each sample holding rack carries spaced-apart flat springs tensioned outwardly to operate timing mechanism located on the guideway. When the sample is assembled on the holding rack these springs are held in retracted position by spaced threads which cross the upper surface of the test sample. The threads (ordinarily of cotton) are readily ignited and are so positioned that the first flash of material will cause one of these threads to be burned to release its spring

2

and thereby initiate a timing operation. The second thread is spaced a predetermined distance from the first and when the second thread is burned, its spring likewise is released to control a second timing operation.

In the preferred form, the holding rack has its bottom portion so shaped that a segment of the test film will be substantially vertical in the cabinet, whereas the main portion of the film will be in a slanting position. By providing this bottom vertical segment of the test film and by positioning one of the control threads near the top of this segment, such thread will be burned by the first flash of flame resulting from the ignition of the test sample. This operates mechanism which will measure the elapsed time between the operation of the switch controlled by the insertion of the rack, and the time when the flash burns the first thread.

It is also contemplated that the burning of the first thread will initiate a second timing operation which will be terminated by the burning of the second thread. The elapsed time between these two will measure the burning rate of the main body portion of the sample.

The actual angle of the slanting portion of the test film is not critical. Ordinarily a slope of 45° is preferred but an angle of from 25° to 75° relative to the base of the cabinet is operable. Furthermore, while I prefer to use two threads to measure the ease of ignition and rate of burning, the greater number may be used if desired.

Ordinarily the timing mechanism will consist of electrically operated clocks but mechanically operated clocks may be employed if desired.

The two members of the holding rack may be clamped together in any desired fashion or if the samples to be tested are of more or less uniform thickness they can be hinged together at the upper end and clamped at the lower end.

While I prefer to ignite the test sample with a flame I may, under some circumstances, get valuable results using an electrical igniter such as a hot wire.

In order to get a further type of measurement from my structure, I find it advisable to provide means for measuring the temperature of the flame resulting from the test sample. This may be in the form of any well-known temperature measuring device located above the guideway but preferably a needle thermocouple is employed connected to a pyrometer.

In some cases the samples to be tested will not support combustion. In such case, they must be placed in a flame. For this purpose I provide a

second flame, the size of which can be carefully controlled for purpose of standardization and arrange to have the sample positioned in this flame. In such case automatic timing ordinarily is not feasible and therefore I prefer to supply additional controls for the timing mechanism so that the timing mechanism can be manually operated, as by push buttons.

The cabinet may be provided with vent holes for exit of waste gases, at the top of the side panels. An inlet vent for fresh air may be provided at the bottom of one side panel. The test flame is preferably a butane gas flame of a predetermined size and it is directed at a predetermined and fixed angle onto the film surface. Other gases than butane are operable, for example propane, pentane, water gas, etc. but butane is preferred. A manometer may be provided to measure the gas pressure of the fuel flame.

Also while my apparatus may be used for measuring the ease of ignition and rate of burning in a consecutive manner, it may also be used for individually determining either the ease of ignition or rate of burning of the test sample.

My invention may be readily understood from the example illustrated in the accompanying drawing, in which:

Fig. 1 is a side view of the invention broken away in part to show the assembled sample holding rack in its operable position within the cabinet.

Fig. 2 is a top view showing the electrical clock arrangement.

Fig. 3 is a front view broken away and showing a sectional view of the rack in operable position.

Fig. 4 is a view taken along line 4-4 of Fig. 3 and shows the assembled sample holding rack.

Fig. 5 is a view taken along line 5-5 of Fig. 4 and shows in detail the method of supporting the test film.

Fig. 6 is a view taken along line 6-6 of Fig. 4 and shows in operable relation a threaded tensioned spring adjacent to an electrical switch.

Fig. 7 is a detail view of the front electrical switch broken away in part to show the operating lever.

Fig. 8 is a rear view of the view shown in Fig. 7, and

Fig. 9 is a schematic wiring diagram indicating the manner of operating the electrical clocks.

In these drawings I have illustrated one embodiment of my invention and have shown the same assembled with the sample holding rack in operable position.

A cabinet 20 has a first electrical clock 21, a second electrical clock 22, an electrical switch 23, and a glass door 24 for viewing the manner of combustion of the film. It also has a manometer 25 open to the atmosphere and connected to the gas fuel line at 26.

A sample-holding rack 27 having a top U-shaped element 28 and a bottom U-shaped element 29, is adapted to slide on a guideway 30 with the lower face of element 28 resting on the upper surface of guideway 30, which latter is set at an angle of about 45° to the horizontal by means of short supporting pillars 31 and tall supporting pillars 32. The rack is introduced into the cabinet through side opening 33 and slides into operable position at the bottom of the guideway. The combustion gas is introduced through conduit 34 and conducted to a needle nozzle or jet 35 supported in a movable ball 36 in ball block 37.

The top U-shaped element 28 carries on leg 28a lower flat spring 38 and upper flat spring 39, each having a thread holding notch 40 near its movable end. These springs are fixed to blocks 41 and the limit of travel of the springs may be arrested by stops 42. The leg 28 has also two C-shaped slots 43 to allow for slipping the threads 44 to the underside of the legs of the U-shaped element 28 and into grooves 45 across the face of film 46. Threads 44 are led to the upper side of the leg 28b of element 28 and secured to binding posts 47. An insulated handle 48 is attached to element 28. A flat spring 49 in conjunction with spring 50 secures the film 46 between the top U-shaped element 28 and the bottom U-shaped element 29, each element having a turned-down segment 51 located at the forward end of their respective prongs. These turned-down segments 51 are preferably at an angle of about 45° so that the film held by them will be approximately vertical when the rack is positioned in the cabinet.

A lower front microswitch 52 attached to the front runway of guideway 30 has a lever 53 located over push button 54. The lever 53 is actuated by the lower front leading edge 55 of the top U-shaped element 28. A lower rear microswitch 56 and an upper rear microswitch 57 are attached to the rear runway of guideway 30. Microswitch 56 has a push button 58 actuated by spring 38 whereas microswitch 57 has a push button 59 actuated by spring 39.

In operating my invention I attach cotton threads 44 through the slots 40 of springs 38 and 39 and conduct the threads to the lower side of U-shaped top element 28 by slipping the threads through the C-shaped slots 43. The threads are then pulled across the open space between the two legs of this element and led into the grooves 45 of the leg 28b and finally pulled tight and affixed to binding posts 47 so that the springs 38 and 39 will not contact microswitch push buttons 58 and 59 when the rack 27 is slid into place on guideway 30. The thread connected to spring 38 is designated as 44a and the thread connected to spring 39 as 44b. A shell of combustible material 46 (such for example as a plastic film) is placed in between the top U-shaped element 28 and bottom U-shaped element 29 and is held in fixed position by spring clamps 49 and 50.

After the sample holding rack 27 is assembled, it is inserted into cabinet 20 through opening 33 and slides down on guideway 30. When it reaches the bottom of the slide the sample enters the flame directed from nozzle 35 and at the same time lever 53 is tripped to operate push button 54 of switch 52 thereby starting electrical clock 21. The sample (if of combustible material) will immediately ignite and the first flash of flame will burn thread 44a. This will release spring 38 which will operate button 58 and switch 56, simultaneously stopping clock 21 and starting clock 22. It is important that the device be so constructed that thread 44a will not be burned by the ignition flame but will be burned by the first burst of flame from the ignition of the test sample, in order that the first clock may record the ignition or flash time.

After the initial flash the film burns until thread 44b attached to spring 39 is ignited whereupon this spring will operate button 59 of microswitch 57 to stop clock 22. The time interval recorded on clock 22 records the time of combustion of the film from the first flash until com-

bustion has reached the point where the second thread 44b is burned.

In order to measure the heat of the combustion flame, I may supply a pyrometer 60 to which is connected a thermocouple 61 (See Figs. 3 and 4).

On some occasions it is desired to test the combustion rate of a material which will not itself support combustion. This demands that the material be kept in a flame. For this purpose I supply a burner 64 which can be carefully adjusted to give a standard flame size. This is connected with a pipe 66 which in turn is connected to a source of gas. The sample may be hung at any convenient point within the casing as for example from the hooks 68 (See Fig. 1).

For measuring this type of combustion, manual control is advisable and accordingly I supply a push button 70 for manually operating clock 21, a center post switch 72 for changing the circuit from automatic to manual operation and push button 74 for operating clock 22. The operator can by some practice standardize on the degree of combustion to be measured in any given sample.

The electrical connections are indicated in Fig. 9, in which 76 are the usual prongs for attaching an electrical extension cord, 78 is a transformer and 80 is a pilot light. For automatic operation, center post switch 72 is left in the position shown in Fig. 9 and switch 56 is also initially in the position shown in Fig. 9. Switch 23 is open, switch 57 is closed and both push button switches 70 and 74 are closed. When switch 52 is closed a circuit will be closed through clock 21 starting it in operation. When switch 56 is operated to its other position, the circuit through clock 21 is broken and the circuit closed through clock 22. When switch 57 is operated, this circuit is broken.

For manual operation switch 56 is left in the position shown in Fig. 9 but switch 72 is moved to its other position (its upper position in the figure) and switch 51 is left closed. Switches 70 and 74 are manually opened and toggle switch 23 closed. Clock 21 can be operated by manually closing switch 70 and clock 22 can be operated by closing switch 74. For test purposes, with switch 72 in its upper position and switches 70 and 74 closed, the toggle switch 23 can be used to be sure that both clocks are operating correctly.

With this device we can test a vast number of types of materials and can measure the relative inflammability of them. Thus we have made comparisons between such materials as paper, rubber, various types of plastics including thin-gauge unsupported films, heavy-gauge unsupported films, supported films and rigid sheeting and textile fabrics of all sorts. For example, we have tested broadcloth, medium-weight rayon fabric, rayon chiffon, rayon marquisette, cotton marquisette, corduroy, glazed chintz, single and double-coated rubber fabric, unsupported rubber film, oil-coated cloth, pyroxylin-coated fabric, ethyl cellulose rigid sheeting, vinyl acetate rigid sheeting, unsupported thin and heavy gauge vinyl sheeting, supported vinyl sheeting, polyethylene and chlorinated polyethylene films, paper and cellophane and have found the tester to perform very satisfactorily.

In addition to measuring the rate of ignition and rate of intensity of combustion we have found that the removability of the film holder permits us to withdraw the holder as soon as the second thread has been burned and test the

sample for difficulty of extinguishment by blocking out the fire under standardized conditions.

It is understood that the example given in the specification is intended only by way of illustration and that it may be modified in many details without departing from the spirit of my invention.

What I claim is:

1. An apparatus for determining the flammability characteristics of sheeted material comprising a pair of U-shaped members for holding a sheet to be tested while stretched across the legs of the apparatus with the central portion and one edge of the sheeted material unsupported, means for igniting the sheet at the unsupported edge, means for holding combustible threads across the face of the sheet at predetermined intervals and means controlled by the successive combustion of such threads for measuring the time interval between their combustion.

2. An apparatus as specified in claim 1 which further includes means for holding said members in a sloping position.

3. An apparatus as specified in claim 1, in which the sheet to be tested is held against an under face of the upper one of said pair of U-shaped members and said U-shaped members are supported by the under face of such upper member so that the upper face of the sheeted material is at a predetermined level relative to such support.

4. An apparatus as specified in claim 1 which includes means for measuring the intensity of the heat generated.

5. In an apparatus for determining the flammability characteristics of sheeted material, the combination of a pair of time clocks, means for holding a sample to be tested, a flame for initiating combustion of such sample, means for simultaneously starting one clock and exposing the sample to the flame, automatic means for stopping such clock and starting the second clock when the sample is ignited and burned a predetermined distance and means for stopping the second clock when the sample has burned a second predetermined distance.

6. In a device of the type described, a cabinet, means movable within said cabinet for holding a sample of material with a portion arranged substantially vertical, means adapted to ignite a lower part of said vertical portion of such sample when said holding means is moved into operative position relative to the igniting means, a timing mechanism, means for starting said timing mechanism when the sample holding means is moved into operative position relative to the igniting means, a separate inflammable member positioned adjacent an upper part of the said vertical portion of such sample in position to be ignited by the burning of such sample and said timing mechanism being controlled by the burning of such inflammable member so that when said vertical portion of the sample is ignited at a lower point, a measurement may be taken of the time elapsed before said inflammable member is ignited by a flame from the sample.

7. A combination as specified in claim 6 in which the means for holding the sample comprises a frame and the cabinet is provided with guideways within which said frame is adapted to slide to bring a sample within the frame into operative position relative to the igniting means and which further includes means adapted to be operated by the sliding of said frame to initiate

the operation of said timing mechanism as the sample is ignited.

8. A combination as specified in claim 6 in which said holding means also holds a portion of the sample in non-vertical position and which includes a second inflammable member located adjacent a portion of such sample spaced laterally from the first inflammable member and which also includes a second timing mechanism and means responsive to the burning of said first inflammable member for simultaneously stopping the first timing mechanism and starting the second timing mechanism, said second timing mechanism being controlled by the burning of such second inflammable member to measure the elapsed time for flame to move laterally from the first inflammable member to the second inflammable member.

9. A structure as specified in claim 6 in which the means for holding a sample of material com- 20

prises a U-shaped frame and the means for igniting a sample held in such frame is adapted to ignite the sample at the open end of the U.

10. A structure as specified in claim 6 in which said inflammable member consists of an inflammable thread holding a spring under tension so that when said thread is burned, said spring will be released to operate the timing mechanism associated therewith.

JAMES R. BLEGEN.
